UNITED STATES PATENT OFFICE.

JAMES L. MCQUARRIE, OF MONTCLAIR, NEW JERSEY, ASSIGNOR TO WESTERN ELECTRIC COMPANY, INCORPORATED, OF NEW YORK, N. Y., A CORPORATION OF NEW YORK.

AUTOMATIC SWITCH.

1,284,742.

Specification of Letters Patent. Patented Nov. 12, 1918.

Application filed August 29, 1916. Serial No. 117,429.

To all whom it may concern:

Be it known that I, JAMES L. MCQUARRIE, a citizen of the United States, residing at Montclair, in the county of Essex and State 5 of New Jersey, have invented certain new and useful Improvements in Automatic Switches, of which the following is a full, clear, concise, and exact description.

This invention relates to automatic 10 switches for use in telephone exchange systems, and more particularly to switches of the multiple brush type.

In switches of this type it is customary to first render operative one of a certain set of 15 brushes, after which such selected brush is moved in group steps over the section served by it. At the completion of the group steps, short steps are taken to select a particular terminal set in the selected group.

20 It is the object of this invention to provide a switch of these general characteristics in which simplicity of structure and operation is attained.

A feature of the present invention is the 25 utilization of a single magnet during brush selection and units selection, a second magnet not being used for group selection.

The general structure of the contact bank, brush sets and tripping mechanism may be 30 similar to that disclosed in Patent No. 1,123,696 issued January 5, 1915 to E. B. Craft and J. N. Reynolds.

In the drawing, the structure of the switch embodied in the present invention is 35 diagrammatically shown, as well as a circuit arrangement suitable for operating the same.

The structure of a preferred form of the switch will first be briefly described. A 40 shaft 1 is mounted in any suitable manner for longitudinal motion, a spring 2 tending to cause upward motion of the shaft. The shaft is provided with a plurality of brush sets 3, there being a brush set for each section 4 of the panel contact bank. These brush sets are normally inoperative, but may be made operative by the action of a trip rod 5 carrying tripping fingers 6, and operated by a trip magnet 7. The trip rod 5 and magnet 7 are common to all the brushes of the switch, the brush set to be tripped being determined by the primary motion of

shaft 1, as described in the above mentioned patent.

A lever 14 pivoted at 15 carries at one end 55 a pallet 10, this pallet coöperating with a pallet 9 to form an escapement under the control of magnet 8, and coöperating with pallet 13 to form an escapement under the control of magnet 18. When magnet 8 attracts its armature, pallet 9 is drawn to the left and pallet 10 is forced out of engagement with the first of a series of ratchet teeth 19 by the action of a spacing block 12. The shaft is drawn upward under the tension of spring 2 until the pallet 9 engages the next ratchet tooth 19. Upon the de-energization of magnet 8 pallet 9 is withdrawn, and pallet 10 is forced into engagement with the tooth previously held by pallet 9 by the tension of spiral spring 11. The shaft 1 is moved upward the desired number of steps, at which time trip rod 5 is rotated to release and render operative a set of 65 brushes serving the desired section, it being understood that the tripping fingers 6 are spaced at successively increasing distances from the normal positions of brush sets 3 as described in the previously mentioned patent.

The next series of impulses is directed to magnet 18. When magnet 18 first attracts its armature, pallet 13 is drawn to the right, causing arm 14 to be moved to the right by the action of spacing block 21. This movement of arm 14 causes pallet 10 to be withdrawn from the tooth with which it is in engagement, and the shaft 1 is moved upward a distance such that the tripped brush set 3 is now in engagement with the bottom 90 terminal of the section served by it, the shaft being arrested in this position by the engagement of pallet 13 with the first of a series of ratchet teeth 17. When magnet 18 is deenergized, pallet 13 moves to the left, carrying arm 14 with it under the tension of spiral spring 16. This movement of arm 14 causes pallet 10 to be drawn into engagement with the first of the series of ratchet teeth 20, to hold the switch in position. The operation of magnet 18 allows the shaft to be advanced in steps corresponding to the distance between ratchet teeth 17, it being understood that there are ten ratchet 95 100

teeth 20 in the space equal to the distance between successive ratchet teeth 17. The brush set therefore moves over a group of ten terminals upon each step made by the 5 switch under the control of magnet 18.

At the conclusion of this series of impulses the magnet 8 again becomes operative, either in response to a series of impulses, if the switch is to act as a connector, 10 or in response to circuit conditions such as will cause the switch to hunt for an idle trunk in the group selected, if the switch is to act as a selector. At this time the pallets 9 and 10 coöperate with ratchet teeth 20 15 in the manner described for brush selection, under the control of magnet 8.

The switch is restored by the action of a magnet 22 which attracts its armature to force a driving ribbon 23 into engagement 20 with a constantly rotating roller 24 to draw the switch downward and rewind spring 2. The switch is held in its normal position by the engagement of pallet 10 with the first of the ratchet teeth 19.

25 The operation of the circuit arrangement shown in the drawing is as follows, assuming that the switch is to operate as a selector switch. When the trunk 25, 26 is seized by a preceding switch, line relay 27 is energized over a path from grounded battery, left-hand winding of relay 27, side-switch wiper 28 and its first contact, conductor 26, through the brushes and contacts of preceding switches and the subscriber's circuit, 30 conductor 25, side-switch wiper 29 and its first contact, right-hand winding of relay 27 to ground. Relay 27 attracts its armature and completes a circuit for slow-release relay 30 from grounded battery, winding of 40 relay 30, to ground at the armature and front contact of relay 27. A series of impulses is now sent to select a brush. Upon the first interruption of the line circuit, relay 27 is deenergized and a circuit for slow-release relay 31 is completed from grounded battery, winding of relay 31, armature and front contact of relay 30, to ground at the armature and back contact of relay 27. A circuit is now completed for escape magnet 32 45 from grounded battery, winding of escape magnet 32, armature and front contact of relay 31, side-switch wiper 33 and its first contact, to ground. Escape magnet 32 is energized but does not release the side switch. At 50 the same time a circuit is completed for stepping magnet 8 from grounded battery, winding of magnet 8, side-switch wiper 34 and its first contact, armature and front contact of relay 30, armature and back contact of relay 27, to ground. The shaft makes the desired number of steps in response to the impulses sent, under the control of magnet 8 and its escapement, consisting of pallets 9 and 10. At the conclusion of this series of 55 impulses, relay 27 remains energized for a

relatively long period, whereupon relay 31 releases and opens the circuit of escape magnet 32, which deenergizes and releases the side switch into its second position.

In the second position of the side switch, 70 a circuit is completed for trip magnet 7 from grounded battery, trip magnet 7, side-switch wiper 35 and its second contact, to ground. The trip rod 5 is operated to release the set of brushes serving the desired 75 section, such brush set having assumed a position to be tripped by the tripping finger 6 on such movement of the rod 5.

The second set of impulses is now sent, the circuit to line relay 27 being completed over 80 the side-switch wipers 28 and 29 in their second position. The operation of relays 27, 30 and 31 and escape magnet 32 being exactly similar to that previously described. However, the impulses are now sent to stepping magnet 18 instead of magnet 8 over side-switch wiper 34 and its second contact, this circuit being controlled at the armature and back contact of line relay 27, as before. The shaft is now allowed to advance 90 in long steps, the brush set 3 passing over a group of ten terminal sets upon each actuation of magnet 18. At the conclusion of this series of impulses, magnet 31 is deenergized as before and allows the escape magnet 95 32 to deenergize and release the side switch into its third position.

In the third position of the side switch, magnet 8 interrupts its own circuit at its armature and back contact, this circuit being 100 from grounded battery, winding of magnet 8, armature and back contact of magnet 8, side-switch wiper 33 and its third contact, to ground. Assuming that an idle condition of trunks is represented by the presence of 105 ground on their test terminals, and a busy condition by the absence of such ground, escape magnet 32 will not be energized until an idle trunk is found, the side switch being so constructed that the magnet 32 will release it from its third to its fourth position 110 upon the energization of the escape magnet. The selected brush set 3 will now be advanced over the terminal sets in the desired group until an idle trunk is found, at which time the presence of ground on the test terminal of such trunk will allow escape magnet 32 to energize and release the side switch into its fourth position over a circuit from grounded battery, winding of 115 magnet 32, side-switch wiper 36 and its third contact, test brush of the selected set 3, to ground at the terminal of the idle trunk. In the fourth position of the side switch, the operating circuit for stepping 120 magnet 8 is opened and conductors 25 and 26 are extended to a desired trunk over which further connection may be established.

At the conclusion of conversation, ground 125 will be reapplied to the test terminal of

the selected trunk by the release of the succeeding switch, at which time a circuit will be completed for downdrive power magnet 22 from grounded battery, winding of magnet 22, off-normal contact 37, conductor 38, side-switch wiper 36 in its fourth position, to ground. Magnet 22 in energizing, completes a locking circuit for itself through contact springs 39, controlled by its armature 40, and at the same time forces a driving ribbon 23 into engagement with constantly rotating roller 24, to cause the restoration of the switch. When the switch arrives in its normal position, contact 37 will be opened to break the locking circuit of magnet 22.

The side switch is restored in the usual manner by the return of the brush set, and on leaving position 4 supplies ground for the release of the preceding switch over a circuit from ground, armature and back contact of relay 30, side-switch wiper 40 in either first, second or third positions, and conductor 41, to the test conductor of such preceding switch.

What is claimed is:

1. In an automatic switch, a movable shaft, movable contacts carried thereby, a plurality of stationary terminal sets arranged for engagement by said movable contacts, means for causing a primary selective movement of said shaft, means for causing a secondary selective movement of said shaft, means for causing a tertiary selective movement of said shaft, and a single operating magnet to mechanically control said primary and tertiary movements.

2. In an automatic switch, a movable shaft, movable contacts carried thereby, a plurality of stationary terminal sets, a contact bank containing said terminal sets and arranged to be served by said movable contacts, said terminal sets being arranged in sections and groups, means for selecting a desired section, means for selecting a desired group, means for selecting a desired terminal set in said selected group, and a single operating magnet to directly mechanically control said first and third selecting means.

3. In an automatic switch, a movable shaft, a plurality of multiply-connected brush sets carried thereby, a contact bank divided into sections and groups, there being one of said brush sets per section, said brush sets being normally inoperative with

respect to the section served by them, means for rendering a desired brush set operative, means for advancing said operative brush set in long steps, means for advancing said operative brush set in short steps, and a single magnet to control the means for rendering a desired brush set operative and advancing said shaft in short steps.

4. In an automatic switch, a movable shaft, movable contacts carried thereby, a plurality of stationary terminal sets arranged for engagement by said movable contacts, three series of ratchet teeth mounted on said shaft, the ratchet teeth in the respective series being variously spaced, a magnet and escapement to control movement of said shaft in conjunction with two of said series of ratchet teeth, and a second magnet and escapement to control motion of said shaft in conjunction with the third of said series of ratchet teeth.

5. In an automatic switch, a movable shaft, a plurality of multiply-connected brush sets carried thereby, a plurality of terminal sets, a panel contact bank containing said terminal sets, said bank being divided into a plurality of sections, there being one of said brush sets per section, said brush sets being normally inoperative with respect to the section served by them, means for advancing said movable shaft into a position where a desired one of said brush sets may be made active, means for rendering active said positioned brush set, means for advancing said active brush set in long steps, means for advancing said active brush set in short steps, and a single magnet to control the movement of the shaft during positioning for brush selection and during said short steps.

6. In an electric switch, a plurality of contact banks, contact means individual to said banks to engage contacts of their respective banks, means to select any desired contact means, a spring to move said contact means, means for controlling the movement of the selected contact means to engage any desired contact in its respective bank, and a single means for restoring said contact means and spring to normal.

In witness whereof, I hereunto subscribe my name this 26th day of August A. D., 1916.

JAMES L. McQUARRIE.
